UNITED STATES PATENT OFFICE.

HENRY RITHNER, OF WELLSBURG, WEST VIRGINIA.

HOOD HOLDER FOR ELECTRIC LAMPS.

Application filed November 20, 1924. Serial No. 751,140.

This invention relates broadly to hoods for electric lamps, and more specifically to a hood for light bulbs and attaching means therefor.

5 The primary object of the invention is to provide a glass hood of that type commonly employed for embracing or enclosing the lamps of electric signs, and simple, efficient and improved means whereby the hood is 10 yieldingly mounted upon and supported by a lamp.

A further object is to provide a hood having attaching means which not only maintains it firmly in its applied position, but 15 also provides for its ready and convenient application to and removal from a lamp.

In describing the invention in detail, reference is herein had to the accompanying drawings, in which—

20 Figure 1 is a sectional elevation of the invention, applied;

Figure 2 is a plan view of the attaching member;

25 Figure 3 is a view similar to Fig. 1, showing a modified form of the invention;

Figures 4 and 5 are, respectively, a side elevation and a plan view of a modified form of attaching member or ring.

Referring to said drawings, 1 indicates an 30 ordinary form of electric lamp of the type commonly employed in electric signs, and 2 designates a preferred form of hood for such a lamp. Said hood is made of colored or translucent glass and is shaped to constitute an enclosure for the larger outer end portion of the lamp, being designed to color the transmitted light rays emanating from the lamp filament. Said hood has an internal diameter slightly greater than the greatest 35 diameter of the lamp and is provided with an internal annular shoulder 3 which, in the preferred short form of hood shown in Fig. 1, is located adjacent to the open end, or mouth, of the hood.

40 An open ring 4 formed of resilient wire is employed as an attaching device and retainer for the hood 2 which is adapted to be slipped into place upon the lamp without removal of the latter from its socket. Said

45 ring is bent into substantially zigzag shape, forming a series of alternate forwardly and rearwardly extending fingers which are inclined with respect to the axis of the lamp, the terminals 5 of the forwardly extending

50 fingers being resiliently held seated beneath or behind the shoulder 3 while the terminal

portions 6 of the rearwardly extending fingers occupy seated gripping relation to the lamp at points located rearward with respect to said shoulder and also with respect 60 to the line of the greatest circumferential dimension of the lamp.

The ring 4 being first fitted in place within the hood, the latter is applied to the lamp by forcing it axially rearward over the outer 65 end of the lamp. As the hood is being so

forced into place, the finger portions 6 are gradually expanded through engagement therewith until they have passed over the greatest circumference of the lamp, whereupon 70

said fingers contact upon the lamp, gripping the latter with such pressure that the therewith interlocked hood is thereby firmly supported in place. During applica- 75

tion of the hood, as aforesaid, the wire ring is forced forward within the hood away from the shoulder 3 to the extent that wedg- 80

ing of the ring between the lamp and said shoulder is prevented. When, however, the hood is retracted, as for withdrawing it from 85

the lamp, the ring becomes wedged between said shoulder and the lamp and thus effec- 90

tively resists such withdrawal, either by chance or design. To effect intended with- 95

drawal, one end of the ring must first be 100

grasped by hand and drawn out in the direc- 105

tion of the lamp base, thus gradually to strip lengthwise said ring from the hood, whereupon the latter is wholly freed. To facil- 110

itate such freeing of the hood, one end of the ring is extended rearward so that it will lie outside the hood mouth and is bent to form a hook 7 which is adapted to rest upon or against the mouth-end of the hood when the latter is mounted on the lamp, as shown 115

in Fig. 1.

In the modification shown in Fig. 3, the hood 2^a is made of such greater length and depth that it will enclose substantially the entire lamp 1. Such hood has formed there- 120

in an internal annular rib which affords a shoulder 3^a for the retaining ring 4^a, said rib being located at such a depth in said hood that the therewith-engaged ring will 125

occupy proper position for gripping the lamp rearward of and adjacent to the portion of the lamp having the greatest circum- 130

ference. Also, the ring 4^a has a long rear- 135

ward extension 8 at one end thereof termin- 140

ated by a hook 7^a for overlying the edge 145

of the mouth of the hood, as shown in Fig. 2, said extension and hook constituting a pull 150

member which may be grasped by hand to effect stripping of the ring from the hood when removal of the latter is sought.

The modified form of retaining ring shown in Figs. 4 and 5 is designed yielding-
ly to resist removal from the lamp of the hood to which it is applied and at the same
time to permit of forcible removal, if de-
sired, without detaching it from the hood.
5 Said ring, which preferably has its ends
joined by a sleeve-like clip 9, comprises rela-
tively long base portions 5^b which are adapt-
ed to seat forward of the annular shoulder
of the hood, and a plurality of short rear-
wardly and inwardly inclined V-shaped fin-
gers 6^b adapted to seat in yieldingly gripping
relation to the lamp. In withdrawing
the hood which carries said ring, the gradu-
ally expanding pressure to which the fin-
gers 6^b are subjected acts to force the ring
forward within the hood slightly, or to the
extent that the tips of said fingers ap-
proach the shoulder of the hood so closely
that they are allowed to pass by the great-
est diameter of the lamp without wedging.

20
25

What is claimed is—

1. A hood retainer for electric lamps,
comprising, in combination with a hood hav-
ing an internal annular rib forming a shoul-
der, a resilient wire ring adapted to be
sprung into and out of expanded seating re-
lation to the hood walls inward of said
30

shoulder, said ring being shaped to form
alternate inwardly and outwardly extend-
ing inclined fingers, of which the inwardly
extending fingers yieldingly engage the hood
and the outwardly extending fingers are
adapted yieldingly to engage a lamp en-
closed by said hood.
35

2. A hood retainer for electric lamps, 40
comprising, in combination with a hood hav-
ing an internal annular shoulder, an open
resilient wire ring for seating within said
hood inward of said shoulder and having
fingers for yieldingly gripping a lamp en-
closed by said hood, one of the ends of said
ring being directed outward and engaged
with the edge of the mouth portion of the
hood.
45

3. A hood retainer for electric lamps, 50
comprising, in combination with a hood hav-
ing an internal annular shoulder, an open
resilient wire ring for seating within said
hood inward of said shoulder and having
fingers for yieldingly gripping a lamp en-
closed by said hood, one of the ends of said
ring being directed outward and having
formed thereon a terminal hook adapted to
seat upon the edge of the mouth portion of
the hood.
55

In testimony whereof, I affix my signature.

HENRY RITHNER.
